UNITED STATES PATENT OFFICE.

WILLIAM A. RINGLER, OF PHILADELPHIA, PENNSYLVANIA.

SAVINGS SYSTEM.

Application filed April 18, 1925. Serial No. 24,005.

The object of this invention is to devise a novel savings system wherein the usual complicated system of keeping records of payments and of working out the interest which is due to the depositor is eliminated.

With the above and other objects in view, my invention comprehends a novel savings system wherein the receipt slip or the depositor's folder and the bank receipt card can be simultaneously receipted and a symbol indicative of the interest to which the depositor is entitled can also be simultaneously applied to the folder and card.

It further comprehends novel means for simultaneously dating the depositor's receipt and the bank receipt card and for rendering the symbol operative or inoperative, so that if a deposit is not made on time the interest symbol will not be printed on the depositor's slip or on the receipt card.

Other novel features of construction and advantage will hereinafter more clearly appear in the detailed description and the appended claims.

For the purpose of illustrating the invention, I have shown in the accompanying drawing a typical embodiment of it, which in practice, will give reliable and satisfactory results. It is, however, to be understood that this embodiment is typical only and that the various instrumentalities of which my invention consists can be variously arranged and organized, and that the invention is not, therefore, limited to the precise arrangement and organization of these instrumentalities as herein set forth.

Figure 1 is a plan view of an envelope adapted to receive the depositor's receipt slip.

Figure 2 is a plan view of the depositor's receipt slip.

Figure 3 is a plan view of the opposite side of the depositor's receipt slip.

Figure 4 is a plan view of the one face of the bank card.

Figure 5 is a plan view of the other face of the bank receipt card.

Figure 6 is a section on line 6—6 of Figure 7.

Figure 7 is a sectional plan view through the duplicate dating stamp with the assembled depositor's receipt slip and the bank card inserted therein.

1 designates a depositor's receipt slip which is in the form of a folded card, the outer faces of which are provided with con-

secutively numbered spaces as at 2, and the front face of the slip and its upper and lower portions has indicated, as at 3, the year for example 1925, and as at 4, the number of the depositor's slip. At the bottom of each column of spaces is indicated, as at 5, the amount which is to be deposited each week.

The inside of the folder has a place, as at 6, to indicate the name and address of the depositor, and also the rules and regulations 65 7, which may vary in practice.

For the purpose of fully explaining my invention, I have indicated at 7 a space for 70 rules and regulations which can be employed for a Christmas saving fund.

At 8, is a space for indicating the date on which the fund is withdrawn and also the amount, and at 9, is a place for the signature 75 of the depositor.

In conjunction with this depositor's receipt, a bank receipt filing card 10 is employed having on one face consecutively numbered spaces arranged in columns, as at 11, and, at the top portions, the year, as at 12, and the number of the receipt card, as at 13, which number corresponds to the number 4 of the depositor's slip 1. This face has also indicated on it preferably at the 80 top portion, as at 14, the amount of each separate deposit.

The outer face of the card, as at 15, has a place for the signature and address of the depositor, the number of his account and 90 the date of his birth.

Below this as at 16 is printed or indicated—"I herewith agree to the rules and regulations of the Save-for-Xmas-Fund," and a 95 place is provided for the signature of the depositor.

The bottom portion of the card is separated by lines into spaces 17 and 18, the space 100 17 being adapted to receive any desired data relating to the account, and the space 18 being adapted to receive the date when the account is paid and also in separate column spaces in which to record the deposits and interest-merits and their totals.

In connection with the depositor's slip 105 and the bank receipt card, I preferably employ a duplicate dating stamp, the general construction and operation of which is conventional, except that the duplicate dating stamp is provided with a base 19 which extends beneath an aligning slot 20, and a slide 21 is provided having end portions or

tongues 22, which, when the slide is moved inwardly, will prevent the symbols, such as for example the stars 23, from being printed on both the depositor's slip and the bank receipt card.

The slide 21 has its ends guided beneath the strips 24 carried by the base 19.

25 is an envelope to receive the depositor's receipt and this envelope may if desired have 10 indicated on it as at 26 the latest weekly dates on which payments are to be made to entitle the depositor to receive interest.

The manner in which the savings system is used will now be apparent to those 15 skilled in this art and is as follows:—

When a depositor desires to open an account, his name and address is filled in at the place 6 on the depositor's receipt 1 and also at 15 on the bank card 10. The depositor signs the bank card below the printed matter 16.

When a depositor makes a payment he brings in the deposit slip and makes one or more payments as he may desire. The bank 25 clerk inserts the bank card between the leaves of the deposit slip 1 so that the lines are in register and then moves the aligned deposit slip and card into the duplicate dating stamp, and the date on which the payment 30 is made is simultaneously indicated on both the deposit receipt and the bank filing card.

If the payment is made on time or ahead of time and the depositor is entitled to interest, a symbol, such as for example a star, 35 is stamped on the aligned spaces on both the deposit receipt and the bank card in proximity to the date of payment. If payment is made late or if the depositor is not entitled to an interest credit, the slide 21 is moved inwardly so that the interest credit stars will not be printed.

The depositor and the bank each have an accurate record of the payments which have 45 been made and of the interest to which the depositor is entitled.

My present invention is not limited for use with savings systems but can be used in other cases where payments on the 50 installment plan are made.

In order to economize material I employ consecutively numbered spaces arranged in columns, the numbers on one column reading in a reverse direction to the numbers on 55 the other column on both the deposit slip and on the bank filing card.

The deposit slip 1 may be reinforced by means of a strip 27 of cloth or paper secured to it in any desired manner for example by adhesive material.

As will be understood by reference to Figures 2 and 4 the time on which payments are due may be indicated on both the depositor's receipt and the bank receipt cards. 65 I have shown in these due dates on a few of

the spaces but it will be understood that, if used, each space would have indicated on it the date on which a payment is due.

Having thus described my invention, what I claim and desire to secure by Letters Patent, is:

1. Means for conducting a savings system, comprising a deposit receipt in the form of a folded strip having on one outer face a column of consecutively numbered spaces 75 and on its other outer face a column of consecutively numbered spaces reading in a reverse direction to the numbers of the first column, and a bank filing card having on one face columns of consecutively numbered 80 spaces, one column of which reads in a reverse direction to its other column, whereby when one edge of the bank card is inserted and nested in the folder one of its columns will be covered and the spaces in its other column will register with correspondingly numbered spaces of the deposit receipt to enable the stamping of duplicate dates, and when the bank card is reversed and its opposite edge inserted into the folder, only the 90 numbered spaces reading in a reverse direction will be visible and will register with the visible correspondingly numbered spaces of the deposit slip to enable the stamping of duplicate dates. 95

2. Means for conducting a savings system, comprising a deposit receipt in the form of a folded strip having on one outer face a column of consecutively numbered spaces and on its other outer face a column 100 of consecutively numbered spaces reading in a reverse direction to the numbers of the first column, and a bank filing card having on one face columns of consecutively numbered spaces, one column of which reads in a reverse direction to its other column, whereby when one edge of the bank card is inserted and nested in the folder one of its columns will be covered and the 105 spaces in its other column will register with correspondingly numbered spaces of the deposit receipt to enable the stamping of duplicate dates, and when the bank card is reversed and its opposite edge is inserted into the folder, only the numbered spaces reading in a reverse direction will be visible and will register with the visible correspondingly numbered spaces of the deposit slip to enable the stamping of duplicate dates. 110

3. Means for conducting a savings system, comprising a deposit receipt in the form of a folded strip having on one outer face a column of consecutively numbered spaces and on its other outer face a column of consecu- 115

125

130

tively numbered spaces reading in a reverse direction to the numbers of the first column, and a bank filing card having on one face columns of consecutively numbered spaces, 5 one column of which reads in a reverse direction to its other column, whereby when one edge of the bank card is inserted and nested in the folder one of its columns will be covered and the spaces in its other column 10 will register with correspondingly numbered spaces of the deposit receipt to enable the stamping of duplicate dates, and when the bank card is reversed and its opposite

edge inserted into the folder, only the numbered spaces reading in a reverse direction 15 will be visible and will register with the visible correspondingly numbered spaces of the deposit slip to enable the stamping of duplicate dates, said bank card having on the reverse face of the column carrying face, 20 a suitably designated space for the name and address of the depositor and a suitably designated space for the date paid out and the total of deposits and interests paid out.

WILLIAM A. RINGLER.
